CLAIM

The ornamental design for a cleaning robot with sweeping and mopping parts as shown and described.

DESCRIPTION

1. Cleaning robot with sweeping and mopping parts

1.1 : Front

1.2 : Back

1.3 : Enlarged

1.4 : Left

1.5 : Right

1.6 : Top

1.7 : Bottom

1.8 : Perspective

1.9 : Enlarged

1.10 : Enlarged

1.11 : Perspective

1.12 : Enlarged

1.13 : Perspective

1.14 : Enlarged

1.1, 1.2 and 1.4 to 1.7 are six orthographic projection views of a cleaning robot with sweeping and mopping parts, 1.8, 1.11 and 1.13 are three perspective views thereof, 1.3 is an enlarged view of part A in 1.2, 1.9 and 1.10 are two enlarged views of parts B and C in 1.8, respectively, 1.12 is an

(Continued)

enlarged view of part D in 1.11, and 1.14 is an enlarged view of part E in 1.13; the broken lines in the reproductions of the cleaning robot with sweeping and mopping parts depict portions that form no part of the claimed design.
